UNITED STATES PATENT OFFICE.

JAMES ARTHUR SPEER, OF ROZEL, KANSAS.

SWINGING TABLE.

Application filed August 8, 1925. Serial No. 48,983.

This invention relates to swinging tables for use on bed rails for the accommodation of the sick.

The object of the invention is to construct 5 a table of this character which may be adjustable vertically and laterally at any angle over the bed and which is equipped with a tray adjustable in various directions so that it may be used not only as a table to 10 support food but may be used as a book holder as well.

Another object of the invention is to provide a table of this character which is cheap 15 to construct and which may be readily collapsed to occupy a minimum amount of space when not in use.

With the foregoing and other objects in view which will appear as the description 20 proceeds, the invention resides in the combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings:—

Figure 1 represents a side elevation of a 30 table constructed in accordance with this invention with parts broken out for convenience in illustration and shown clamped to a bed rail which is shown in transverse section;

Figure 2 is a top plan view thereof with 35 parts broken out;

Figure 3 is a longitudinal section taken on the line 3—3 of Figure 2; and

Figure 4 is a detail showing the clamp 40 which mounts the table on the rail.

In the embodiment illustrated the table constituting this invention is shown mounted on an angle iron bed rail R such as is 45 usually found on metal beds.

This table comprises a tubular post 1 secured by a clamp 10 rigidly to the rail R. This hollow post 1 is equipped at its upper end with a set screw 2 which is designed to adjustably secure a telescoping post member 3 to provide for its vertical adjustment 50 for a purpose presently to be described.

Hingedly connected to the upper end of post section 3 is a laterally extending rod or arm 4 which carries at its front end a tray 20 which will be presently described 55 in detail. A brace 5 is hingedly connected at its opposite ends with sleeves 6 and 7

which are mounted to slide respectively on the post section 3 and the arm 4 as is shown clearly in Figure 1. This brace 5 is designed to support the tray carrying arm 4 60 at any desired angle relative to the post section 3 and which is held in adjusted position by friction stops 8 and 9 carried respectively by the post section 3 and the arm 4. The stop 8 is in the form of a slit 65 clamping ring mounted on the section 3 below the sleeve 6 and the stop 9 is a similar clamping ring mounted in front of the sleeve 7 on the arm 4 so that when the brace 5 is adjusted it will be held against sliding 70 movement.

The tray 20 is preferably made in the form of a wire frame shown clearly in Figure 2 to lighten the structure and on which may be placed an ordinary removable tray 75 or any other plate like structure or which may be used directly for supporting books, magazines and the like if desired. This tray 20 as shown is composed of heavy wire bent to form two wings 21 and 22 connected by 80 parallel wires 23 and 24 which constitute a connecting neck and which are held together by means of a plate 25 having its edges rolled and engaged with the wires 23 and 24 as shown at 26, said rolled edges being cut 85 away midway their ends as shown at 27 and the plate bent to form a bearing 28 between which and the wires 23 and 24 the rod 4 is mounted, and with which the tray is adjustably held engaged by means of a set screw 90 29 entering through the bearing 28 and engaging the rod 4 as is shown clearly in Figure 3. It will thus be seen that by loosening the set screw 29 the tray or table proper 20 may be tilted to one side or the 95 other to adapt the device to be used as a book support or for supporting any other article in an inclined position. This table 20 may be adjusted longitudinally on the rod 4 to any desired point and secured by 100 tightening set screw 29.

The clamp 10 which supports the post 1 on the bed rail is here shown constructed of heavy wire in the form of two substantially L-shaped members 11 and 12 which 105 have interengaging eyes 13 and 14 arranged at the inner edge of the lateral flange of the rail R as is shown clearly in Figures 1 and 4.

The upper ends of these members 11 and 12 are provided with loops 15 and 16 which 110 contact with each other at the rear of post 1 and through which and the post a bolt 17

extends and by means of which the post is secured to the clamp. The loop 16 is bowed to conform to the shape of the post as shown clearly in Figure 2.

5 A cross bar 18 connects the two side members of the clamping jaw 12 and has an outwardly bowed portion 19 which fits over the lower end of post 1 and thus securely holds it engaged with the bed rail R.

10 The post section 1 is designed to remain permanently on the bed rail and the telescoping section 3 is removably engaged therewith by the set screw 2 so that when the table is not desired for use section 3 may be lifted out of post 1 and the arm 4 folded or not as desired.

15 It is of course understood that the table need not be removed after each use but may be swung around out of the way and if desired the arm 4 may be elevated so that it will

not interfere with nurses and others waiting on the patient.

I claim:

20 A post securing clamp embodying pivotally connected sections, each of said portions including right angled members adapted to fit around an angle bar of a bed frame, one of said sections having a curved upper portion to receive the post, a cross bar having a bulged portion carried by one of the 25 sections and adapted to engage the post to hold the post into engagement with the angle bar, and means adapted to extend through the post and engage one of the sections to hold the sections and post together. 30

25 In testimony that I claim the foregoing as my own, I have hereto affixed my signature.

JAMES ARTHUR SPEER.
